HEATING SYSTEM

Filed May 11, 1922

UNITED STATES PATENT OFFICE.

JOHN C. HORNUNG, OF GLENCOE, ILLINOIS.

HEATING SYSTEM.

Application filed May 11, 1922. Serial No. 560,107.

To all whom it may concern:

Be it known that I, JOHN C. HORNUNG, a citizen of the United States, residing at Glencoe, in the county of Cook and State of Illinois, have invented a certain new and useful Improvement in Heating Systems, of which the following is a full, clear, concise, and exact description.

My invention relates to apparatus employing pilot burners, such as are employed in automatically regulated furnaces of heating systems, though the invention is not to be limited to any particular use to which it is put. The apparatus of my invention includes a nozzle in heating relation to a boiler or other element that is to be heated, an ignition burner for igniting the fuel passing from the heating nozzle and a pilot burner in igniting relation to the ignition burner.

20 The volume of the pilot flame is small in relation to the volume of the ignition flame whose volume, in turn, is small in relation to the heating nozzle flame. The ignition flame is normally extinguished but such flame is required because the pilot flame is too small in volume to insure establishment of the heating flame when required.

Hitherto the intermediate flame, furnished by the ignition burner, was not employed, 30 a constant pilot flame of sufficiently large volume being maintained for establishing the flame at the heating nozzle.

The pilot flame of my equipment need thus be very small as compared with the pilot 35 flames hitherto employed whereby there is material saving in fuel that is consumed by such flame.

While heating apparatus thus equipped finds a very important use in house heating 40 systems, it is obvious that the invention need not be thus limited.

Pilot burners, as hitherto arranged, are apt to have their flames very readily extinguished by accidental drafts.

45 In accordance with one feature of my invention the pilot flame issues through a hole that is formed in an expansion or thermostatic element that is provided over the pilot burner. This expansion element preferably also constitutes a guard to keep the pilot flame from being extinguished. Where the pilot flame is employed in igniting another flame, as in a furnace, the pilot burner and its guard are contained in a closure in 50 which the burner for the flame that is to be

ignited by the pilot flame is also contained, the flame that is ignited by the pilot flame issuing through an aperture in the closure, this aperture being above the guard for the pilot flame. The walls of the closure supplement the guard in protecting the pilot flame against accidental extinction.

60 I will explain my invention more fully by reference to the accompanying drawing showing a diagram of a heating system embodying the invention.

The heating system illustrated includes a steam boiler 1 furnishing steam to steam radiators located where heat is to be furnished, one such radiator being indicated 70 at 2. The boiler is provided upon any usual or suitable boiler setting 3 that affords a combustion space or fire box 4 in heating relation to the boiler. The furnace is shown as being adapted to the burning of oil or 75 other liquid fuel furnished from a tank 5 through piping 6 that terminates in a heating nozzle 7 which is positioned to discharge the fuel into the fire box. The oil is desirably atomized, to which end the pipe 6 is surrounded by an air pipe 8, space intervening 80 between the two pipes for the passage of air under pressure in the direction of the nozzle 7. This air finds passage through the atomizing nozzle 9 that serves to atomize the 85 liquid fuel as it issues into the furnace fire box 4 and to promote the flow of such fuel in the pipe 6. Air under pressure is desirably furnished by means of an air pump 10 which is driven by an electric motor 11 connected therewith. This pump is directly connected with the pipe 8 in order to effect the forced flow of air through the same and its nozzle 9. Said pipe has a branch 12 which extends into the top of the tank 5 to create 90 air pressure upon the liquid fuel in this tank, fuel being forced through said pipe by the direct action of air pressure within the tank and by air suction at the nozzle 9.

95 The fuel, liquid or otherwise, issuing at the nozzle 9 is ignited by a flame established at the ignition burner 13 whenever the flame at the nozzle 9 is to be formed. A pilot burner 14 normally maintains a pilot flame 15 in igniting relation to the gas that is caused to issue at the burner 13 whenever the ignition flame is to be established.

100 Whenever the motor 11 is set into operation forced flow of air follows in the pipe 8 with the results hitherto stated, a forced 105

110

flow of air being simultaneously established from the pipe 8 through its branch 16 into the valve box 17 against a diaphragm 18 that is mounted within this box and divides the same into two non-communicating compartments. This diaphragm carries stems 19 of a valve 20 that is normally held in closing relation to the intake end of the ignition burner pipe 21 by the action of the diaphragm supplemented by a spring 22. The valve and the intake end of the pipe 21 are upon the same side of the diaphragm 18 with the inlet end of a gas pipe 23 through which gas flows into the box to be passed to the ignition burner 13 whenever flame is to be established at this burner to ignite the atomized fuel issuing from the nozzle 9. A small branch pipe 24 constantly supplies gas to the pilot burner 14 in readiness to ignite the gas that flows through the pipe 21 whenever the valve 20 is opened as a consequence of the air pressure exerted upon the diaphragm 18 by the air forced through the pipe 16 when the motor 11 is driven. The flame at 13 is desirably maintained during the time that fuel is flowing from the nozzle 9 to insure the burning of this fuel during the entire time that it is flowing. When the requisite degree of heat has been produced the motor 11 is thrown out of circuit to stop the flow of air through the pipe 8 whereupon the diaphragm 18 and the spring 22 are permitted to perform their function of closing the valve 20 to extinguish the burner flame at 13, the tiny flame at the pilot burner 14 remaining as it is supplied with gas directly from the pipe 23 independently of the pipe 21.

I will now describe the electric switching equipment by which the motor 11 is brought into and out of circuit due to the thermostatic control effected in the room where the temperature is to be regulated and which motor is cut out of service with or without the coincident operation of the room thermostat when the boiler pressure becomes excessive or the pilot flame at 14 is extinguished.

The electric controlling system illustrated employs a generator 25, in this instance illustrated as an alternating current generator, that supplies current to the distributing mains 26. The motor 11, that is in driving relation with the air pump 10, is connected in bridge of the mains together with switches 27, 28 and 29, 30. The switch arm 27 has its position governed by an arm 31 and a floating block 32, the arrangement being such that when the arm 31 is turned to the right the arm 27 is turned to the left and vice versa. A spring 33, when free to function, moves the arm 31 to the left to cause the arm 27 to move to the right to open the gap in the motor circuit that is normally maintained closed by the arm 27 and

its contact 28. The thermostatic plunger rod 34 is normally influenced by the heat of the pilot flame 15 to place and hold the arm 31 in its right hand and normal position, whereby the switch 27, 28 is normally closed. The rod 34 is assembled with a guard 35 that is formed with a hole 36 therein through which the pilot flame is directed. The guard 35 is a thermostatic continuation of the rod 34 and forms, together with this rod, a thermostatic element whose elongation is normally effected by the pilot flame to place the arms 31 and 27 in their switch closing positions to permit the switch 29, 30 to close the motor circuit when the heat furnished by the radiator 2 is insufficient. If the pilot flame should become extinguished the thermostatic or expansion element 34, 35 will become contracted to permit the spring 33 to move the arm 31 to the left to position the arm 27 to the right to open the motor circuit and prevent the re-establishment thereof when the switch 29, 30 is closed and while the pilot flame is extinguished. Thus the motor 11 is prevented from supplying fuel to the furnace in the absence of the pilot flame whereby a flooding of the furnace with unburned fuel is avoided. The mechanism including the elements 27, 28, 31 and 32 is covered by my United States Patent 1,312,692, dated August 12, 1919, and need not be more fully described herein.

In order that the thermostatic or expansion element 34, 35 may function as described the parts 27, 28, 31, 32 and 33 are carried upon and within a box 36 connected by means of a tube 37 with a bracket 38 upon which the thermostatic element 35 is mounted, the element 35 being positioned to be more subject to the heat of the burner flame than the complementary thermostatic element 37 whereby the rod 34 may be moved longitudinally of its axis and with respect to the tube 37 and the adjacent wall of the box 36 through which said rod slides, an arrangement covered by my co-pending application Serial No. 471,804, filed March 23, 1921.

The mechanism which governs the position of the switch arm 29 has parts similar to parts of the mechanism which governs the position of the arm 27, similar reference characters with prime exponents being applied thereto. The plunger rod 34', however, is operated by a thermostat 38 that is constructed to be responsive to the temperature furnished by the radiator 2.

The flame of the burner 13 issues through an opening 39 between the burner and the brackets whereby the pilot flame is guarded against extinction. The thermostatic element 35 also constitutes a guard for the pilot flame further to guard this flame from extinction. The bracket 38 is desirably con-

tinued to form a pilot flame enclosing box to prevent, as far as possible, drafts from reaching the interior of this box and the pilot flame therein, the guard 35 preventing any drafts that may happen to be present in this box from reaching the pilot flame.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. In a heater, the combination with a heating nozzle; of an ignition burner in igniting relation to fuel flowing through the nozzle; a pilot burner in igniting relation to fuel flowing through the ignition burner; means for establishing flow of fuel through the heating nozzle; and means, operated by the aforesaid means, for establishing and cutting off flow of fuel through the ignition burner while flame is maintained at the pilot burner.

2. In a heater, the combination with a fuel conducting pipe; of an air conducting pipe terminating adjacent the discharge end of the fuel conducting pipe; an ignition burner in igniting relation to fuel flowing through the fuel pipe; valve mechanism for controlling the flow of fuel through said burner; means for effecting forced passage of air through the air conducting pipe in the direction in which fuel is flowing in the fuel conducting pipe and for effecting the forced passage of air upon the valve mechanism to open the valve; and a pilot burner in igniting relation to fuel flowing through the ignition burner.

3. In a heater, the combination with a fuel conducting pipe; of an air conducting pipe terminating adjacent the discharge end of the fuel conducting pipe; an ignition burner in igniting relation to fuel flowing through

the fuel pipe; valve mechanism for controlling the flow of fuel through said burner; means common to the air conducting pipe and said valve mechanism for effecting forced passage of air through the air conducting pipe in the direction in which fuel is flowing in the fuel conducting pipe and for effecting the forced passage of air upon the valve mechanism to open the valve; and a pilot burner in igniting relation to fuel flowing through the ignition burner.

4. In a heater, the combination with a fuel conducting pipe; of an air conducting pipe terminating adjacent the discharge end of the fuel conducting pipe; an ignition burner in igniting relation to the discharge end of the fuel pipe; valve mechanism for controlling the flow of fuel through said burner; a branch pipe for conveying air from the aforesaid air conducting pipe to the valve mechanism that is adapted to open its valve when subject to air under pressure; an air pump for effecting the forced passage of air through said air conducting pipe and its branch; and a pilot burner in igniting relation to fuel flowing through the ignition burner.

5. In a heater, the combination with a fuel conducting pipe; of an air conducting pipe terminating adjacent the discharge end of the fuel conducting pipe; an ignition burner in igniting relation to the discharge end of the fuel pipe; valve mechanism for controlling the flow of fuel through said burner; a branch pipe for conveying air from the aforesaid air conducting pipe to the valve mechanism that is adapted to open its valve when subject to air under pressure; an air pump for effecting the forced passage of air through said air conducting pipe and its branch and through said fuel conducting pipe; and a pilot burner in igniting relation to fuel flowing through the ignition burner.

In witness whereof, I hereunto subscribe my name this fifth day of May A. D., 1922.

JOHN C. HORNUNG.
